UNITED STATES PATENT OFFICE.

LACEY Y. WILLIAMS, OF TOLEDO, OHIO.

DUST-GUARD.

1,223,650.

Specification of Letters Patent. Patented Apr. 24, 1917.

Application filed May 17, 1916. Serial No. 98,089.

To all whom it may concern:

Be it known that I, LACEY Y. WILLIAMS, a citizen of the United States, residing at Toledo, in the county of Lucas and State of Ohio, have invented certain new and useful Improvements in Dust-Guards, of which the following is a specification.

The object of the invention is the production of a metallic dust guard for car journal boxes which shall be effective in excluding dust and dirt from the rear of the box, durable in service, simple in construction, and which can be manufactured cheaply and sold at a relatively low price.

15 The invention consists in stamping to the required shapes from thin metal, preferably sheet steel, two complementary parts, each having a flange bounding an opening and adapted to surround a journal and a flange at substantially right angles thereto, one of said latter flanges being preferably slightly dished, and uniting said parts by inserting one flange bounding the opening within the other similar flange and bending the edge of 20 the flange or upsetting the same to hold the parts together.

It further consists in certain novelties of construction in shape and in the combination of parts as herein set forth and claimed.

30 The accompanying drawing illustrates an example of the embodiment of the invention constructed and the parts combined according to the best mode of procedure I have so far devised for the purpose.

35 Figure 1 shows a journal box in vertical section, a journal in elevation, and one of my improved dust guards in the chamber and also in section.

Fig. 2 is an enlarged face or plan view of 40 a complete guard.

Fig. 3 is an edge view of Fig. 2.

Fig. 4 is a section on line 4-4 of Fig. 2.

Fig. 5 is a section on line 5-5 of Fig. 2.

The guard is comprised of two complementary parts A, B, each of which may be and preferably is fashioned by cutting to shape a resilient metal blank, cutting a circular opening therein, bending the edge of the metal defining the opening outwardly to 45 form a flange C at right angles to the plane of the blank and turning the entire or part of the outer edge of the blank slightly, as at D, so the edge of the metal will easily move in frictional contact with the surfaces of the

metal bounding the dust guard chamber 55 when the guard is in use.

The fashioning of the blank as above set forth may be effected by dies. Both parts A and B are alike except preferably that the flange B is slightly dished, as shown, and one 60 circular flange C of less diameter than the other flange C.

The two units A and B are united by inserting the flange C within the flange C of the other and turning the edge of one flange 65 C at F so as to securely unite them. This latter operation may also be effected by means of a press.

In the completed guard the flanges A and B are spaced apart, the curved edges D ex- 70 tending toward each other, as shown.

The flanges C, C may be of about the width of the box chamber, that is approximately seven eighths of an inch wide when both flanges A, B are at right angles to the flanges 75 C, C. However to cause both flanges A, B to contact with the inner surfaces of the box chamber under pressure and thus form tight joints one of the flanges, as B, may be slightly dished to form with flange C an 80 angle slightly greater than a right angle, as shown by the figures of the drawing. When one of the flanges is dished the flanges C, C may be slightly of less width than seven eighths of an inch as is obvious. 85

The exterior outline of the guard is determined by the shape of the chamber within which the guard is to be inserted, and may vary accordingly.

I designate a journal box of common construction; J the dust guard chamber; and K an axle journal. 90

Upon reference to Fig. 1 it will be seen that a flange C is in frictional contact with the dust guard bearing of the journal, one 95 of the flanges A in contact with the inner surface of the metal bounding the chamber and closing the opening G, and that the edge of the other dished flange B is in contact with the opposite surface closing the 100 opening H, both flanges being pressed against opposite surfaces by the resilience of the metal so that any foreign substance, such as dust or dirt cannot enter the box by way of the journal or by way of the chamber 105 either at the top or bottom.

The guard is first inserted within the chamber and the journal then passed

through the opening in the guard in the usual manner.

What I claim is:

1. A metallic dust guard having a circular flange to engage a journal and two flanges, each with a turned edge, extending outwardly from said circular flange at substantially right angles, said latter flanges being adapted to engage the vertical surfaces of the metal bounding the dust guard chamber.
2. A metallic dust guard having a circular flange to engage a journal and two flanges, each with a turned edge, extending outwardly around said circular flange, one of said two flanges being slightly dished, for the purpose set forth.
3. A metallic dust guard comprised of two parts each having a circular flange and a flange extending outwardly from said circular flange, and the circular flange of one part disposed outside the circular flange of the other part and the edge turned to fasten the two together.
4. A metallic dust guard comprised of two parts each having a circular flange and a flange extending outwardly from said circular flange, the circular flange of one part being disposed outside the circular flange of the other part and the edge turned to fasten the two together; one of said outwardly extended flanges being dished relative to the circular flanges.

ten the two together; one of said outwardly extended flanges being dished relative to the circular flanges.

5. A metallic dust guard comprised of two parts each having a circular flange and a flange extending outwardly from said circular flange, the circular flange of one part being disposed outside the circular flange of the other part and the edge turned to fasten the two together; both of said outwardly extended flanges having their outer edges turned inwardly toward each other.

6. A metallic dust guard having a central opening bounded by a circular flange, and two flanges extending outwardly from and around said circular flange and spaced apart, the outer edges of said outwardly extending flanges being turned toward each other.

7. A metallic dust guard comprised of two parts each having a circular flange and a flange extending outwardly from said circular flange, the circular flange of one part being disposed within the circular flange of the other part, and means for fixedly uniting the two circular flanges; one of said outwardly extended flanges being slightly dished.

In testimony whereof I affix my signature.

LACEY Y. WILLIAMS.
